UNITED STATES PATENT OFFICE

ALBERT WILBUR BAYLIS, OF SCARSDALE, NEW YORK

TERRY CLOTH PRODUCT

Application filed August 3, 1929. Serial No. 383,293.

My invention relates to the method of producing color design in terry fabric and to the product of the method.

Heretofore terry cloth embodying color designs has been greatly limited in the number and types of designs and colors which may be woven into its structure. To those familiar with this particular phase of the weaver's art, it is well known that substantially all color work in terry fabric is the result of the introduction into the structure of dyed filler threads and in some instances dyed warp threads. Inasmuch as these dyed threads take more or less parallel positions in the fabric construction, the colored portions or designs run in straight lines forming bands, checks or so called boxes and it is easily comprehended how few variations in design may be practiced as a result of this condition. In instances where more elaborate designs have been woven into the terry fabric, it has been necessary to resort to the use of a dobby or jacquard attachment for the loom. The dyed threads in this method are still a part of the color scheme and, due to the inherent nature of the terry fabric, the designs are necessarily of large open patterns and of very few colors.

Another means of producing designs in color and of great detail is by the production of chenille products but such products are extremely expensive and are more perishable and are the result of an entirely different art. The production of terry towels having color designs in any part of their structure is then a matter of utilizing dyed yarn and of manipulating the weaving of this yarn in a jacquard so as to produce the patterns.

With the foregoing in mind, it is the purpose of the present invention to produce a terry fabric having a design of any number of colors and of any degree of detail without resorting to the use either of dyed yarn or a jacquard or dobby attachment. I accomplish this object by using printed warp threads which are worked up in the loom as the ground warp of the terry cloth, thereby leaving the terry or top warp to contrast with such of the design which shows through the terry from the ground of the material.

A still further object of the invention is to produce terry towels having no borders so that the fabric may be run sidewise in the loom accompanied by a separate warp which while it is run with the terry warp forming the body of the towel is only a narrow strip at each side and the threads of this extra warp are printed to provide a continuous run of terry fabric of plain weave with printed warp design borders. The material thus made is cut into towel widths and the raw edges suitably bound, the finished towel being a plain center and sides with ends having a design.

The invention will be best understood when taken in connection with the accompanying drawings, in which, Figure 1 is a plan view of a terry towel in the course of manufacture showing the printed warp and the design thereof passing into the material before and after being woven; Figure 2 is a longitudinal section through a partly woven towel showing the ground warp threads having a printed design; and Figure 3 is a perspective view of a corner of a terry towel showing the terry and the design as it would appear when worked up from the printed warp threads;

Referring to the drawings, 10 denotes the printed warp threads which forms the ground warp. The ground and terry warp threads are bound together by the usual binders or filler 12. It will be clear that by the use of a printed warp the latter will carry substantially any design capable of being printed in as many colors as required to produce the desired effect. As the design is printed on the ground or top warp threads, the result is a terry cloth fabric in which is embodied a design of multi-coloring which would be practically impossible to duplicate with even a jacquard attachment.

The design printed on the ground warp threads will not appear long or drawn out because as the ground warp threads run through in a substantially even, smooth condition. It will be seen from the foregoing that by means of my invention, I can produce terry cloth towels, etc. on soft, yieldable material which will embody beautiful patterns, unlimited in the number of colors and type

of design whether florals and leaves in their true colors or other difficult or small, sharply defined patterns. It will also be seen that a floral design such as shown in Figure 1 may be combined with contrasting or similarly designed and well-defined border patterns and in combination with center and border designs may be produced as hereinabove explained by running the material either lengthwise or sidewise into the loom.

10 It will be understood from the foregoing description that the designs and patterns produced by employing my invention are produced by the use of printed warp threads in the manufacture of terry fabric, i. e., towels in contradistinction to the use of dyed yarn or the production of patterns from dyed filler controlled by drop boxes or dobby or jacquard apparatus. The method I employ provides a means for producing very inexpensively, terry towels which have never before been similarly known or produced.

Having now described my invention what I claim and desire to secure by Letters Patent of the United States is:

25 1. A fabric, having a terry surface, and including: a ground warp, a terry warp consisting of a plurality of looped threads, and threads interwoven with said warps to bind them into a finished fabric, said ground warp consisting of threads upon which a design was printed preliminary to the weaving thereof, said design being visible, in the finished fabric, through the loops of the terry warp.

30 2. A fabric, having a terry surface, and including: a ground warp, a warp consisting of a plurality of looped threads, and threads interwoven with said warps to bind them into a finished fabric, said ground warp consisting of threads upon which a design was printed preliminary to the weaving thereof.

35 3. A method of manufacturing terry in which a plurality of warp threads are arranged, some to form a ground warp and some to secure the terry or like effect, including the steps of: imprinting a design on the threads making up the ground warp, and then interweaving with all the warps other filler thread.

40 4. In the manufacture of terry, the production of fabrics having designs visible thereon, including the steps of: preparing ground and terry warps, imprinting a design upon the ground warp, bringing the two warps into their final relation for the production of the fabric, and then interweaving the warps to form the fabric.

45 In testimony whereof I affix my signature,
ALBERT WILBUR BAYLIS.
